We claim the ornamental design for a baby shoe, as shown and described.

CLAIM

FIG. 1 is an isometric view of a baby shoe, embodying our new design;

FIG. 2 is a right side elevational view thereof, the left side elevational view being a mirror image thereto;

FIG. 3 is a front elevational view thereof;

FIG. 4 is a rear elevational view thereof;

FIG. 5 is a top plan view thereof; and,

FIG. 6 is a bottom plan view thereof.
